UNITED STATES PATENT OFFICE.

ENOS CURTISS, OF FINDLAY, OHIO.

JOURNAL-BOX ATTACHMENT.

SPECIFICATION forming part of Letters Patent No. 270,757, dated January 16, 1883.

Application filed October 30, 1882. (Model.)

To all whom it may concern:

Be it known that I, ENOS CURTISS, of Findlay, in the county of Hancock and State of Ohio, have invented certain new and useful Improvements in an Attachment which is to be Applied to Heated Journal-Boxes; and I do hereby declare the following to be a full, clear, and exact description of the invention, such as will enable others skilled in the art to which it pertains to make and use it, reference being had to the accompanying drawings, which form part of this specification.

My invention relates to an attachment which is to be applied to heated journal-boxes; and it consists in the combination of a box or can which holds a suitable cooling and lubricating mixture with suitable clamping devices, whereby the box or can can be attached directly to a heated journal-box and the contents of the can or box be allowed to run into the journal-box for the purpose of cooling it off.

The object of my invention is to provide not only a suitable cooling and lubricating compound for heated journals, but a suitable attachment for carrying the compound, and which attachment is adapted to be quickly and easily attached to almost any lubricating bearing which is used upon railroad-cars.

Figure 1 is a vertical cross-section of my invention. Fig. 2 is a side elevation of the same.

A represents a suitable can or box of any desired shape, size, or construction that may be preferred, and in which a cooling and lubricating compound is carried. Passed around this box, preferably near its lower edge, is a band or strip, C, to which the pronged bearing-plate D is secured by means of suitable bolts. This bearing-plate is not in contact with the band, but is separated therefrom by the thickness of the slotted slide F, which is placed between them. This bearing-plate has a screw-threaded opening through its top at G for the set-screw H to pass through, and has upon each of its lower ends the upwardly curved prong I. This plate, being secured rigidly to the strap or band C, has no movement in any direction, but serves as the bearing upon

which the slotted plate is made to move by the set-screw. This slotted slide F has the set-screw H swiveled in its upper end, and has a slot in each of its downward extensions for the bolts which secure the bearing-plate to the band to pass through. These bolts serve as guides to keep the slide in position and to cause it to always move in a straight line. Upon the lower one of each of the ends of this slotted slide are formed the two prongs O, which preferably project at the angle shown from each other. These lower prongs are made to catch over the edge of the lubricating box or journal, while the prongs I are made to catch inside of it. By turning the set-screw I the prongs can be forced away from each other, so as to secure the box rigidly in place. By moving the prongs close together the two prongs I can be readily inserted inside of any of the journal-boxes now in use when the door or covering is thrown open. In some cases the prongs will be made to catch over the side edges of the box, instead of as here shown, on account of the shape that is given to the openings in some of the boxes. The only difference made is that the parts move laterally instead of vertically.

Having thus described my invention, I claim—

1. The combination of a box or can, a prong-bearing plate secured thereto, a slide having its lower ends formed into bearings, and a screw for adjusting the slide, substantially as set forth.

2. The combination of a can or box having the iron band secured thereto, and the bearing-plate secured to the band, the slide, and the set-screw for moving it, the slide and the bearing-plate being provided with means for the attachment of the box or can directly to the journal-boxes, substantially as described.

In testimony whereof I affix my signature in presence of two witnesses.

ENOS CURTISS.
